ALBERT B. DICK, OF LAKE FOREST, ILLINOIS, ASSIGNOR TO A. B. DICK COMPANY, OF CHICAGO, ILLINOIS, A CORPORATION OF ILLINOIS.

STENCILING MATERIAL.

1,101,259.

Specification of Letters Patent. Patented June 23, 1914.

Application filed March 25, 1913. Serial No. 756,640.

To all whom it may concern:

Be it known that I, ALBERT B. DICK, a citizen of the United States, residing at Lake Forest, in the county of Lake and State of Illinois, have invented certain new and useful Improvements in Stenciling Material, of which the following is a specification.

The invention relates more particularly to the use of stencil-sheets which require for their efficient operation moistening as a preliminary to the striking of the type thereon. Such stencil-sheets are commonly made of Yoshino fiber impregnated with coagulated protein containing an admixture of a suitable tempering ingredient. It has been proposed to combine with such a stencil-sheet a carrier-sheet of hard, firm paper, and to loosely interleave between the stencil-sheet and such carrier-sheet a backing-sheet of absorbent paper or other suitable material adapted to take up a moistening substance, such as glycerin and water. The three sheets are preferably so combined as to be capable of insertion in the typewriter as a unit, and after such insertion the type characters are impressed upon the stencil-sheet, which after drying is adapted for insertion in a duplicator for the production of multiple copies.

I have found that in the use of stenciling material as last described, the backing-sheet, loosely interleaved between the carrier-sheet and the stencil-sheet is open to objection, in that it frequently becomes wrinkled, thereby distorting the overlying stencil-sheet, and moreover the stencil-sheet is liable to injury, not only while inserting the backing-sheet in position but also while applying the moistening material thereto. This is exaggerated by the tendency of the moisture itself to cause the backing-sheet to wrinkle or become distorted. By the present invention, these objections are entirely overcome, and the operation of preparing the stencil greatly facilitated. Essentially, this is due to permanently combining the carrier-sheet and the backing-sheet, the rear surface of the former being firmly bound to the front surface of the latter, so that wrinkling or buckling of the backing-sheet is precluded, whether as a result of careless handling or as a result of the application of the moistening compound thereto.

In the accompanying drawing, the figure 55 illustrates a three-sheet combination, such as that herein suggested, A being the stencil-sheet, B the backing-sheet, preferably of soft, absorbent paper, muslin, or other suitable material, and C the carrier-sheet. The 60 latter is preferably made of stiff, firm paper having a varnished surface, which serves the double purpose of making the carrier-sheet impervious to moisture and of acting as an adhesive for the purpose of binding 65 the backing-sheet B firmly thereto.

The surface of the carrier-sheet is first primed with paraffin and then coated with the varnish, and before the varnish is dry, the absorbent backing-sheet may be laid 70 thereon and the combination of sheets subjected to pressure, during which the process of drying out may continue. As a result, the backing-sheet is firmly, evenly and permanently combined with the carrier-sheet, 75 but is still sufficiently absorptive to enable it to take up the moistening material for the purpose of moistening the stencil-sheet immediately overlying the backing-sheet.

The moistening compound which I employ as part of the present invention consists of water, glycerin and Turkey-red oil. The proportions of these several ingredients may be varied within wide limits, but a practicable formula, for the purposes of this 80 disclosure, is water 72%, glycerin 25%, Turkey-red oil 3%, the purpose of the last named ingredient being to maintain the compound in effective condition throughout 85 an extended period of time. These ingredients being mixed together form a compound which may be evenly applied either by a brush or sponge upon the outer surface of the backing-sheet B, which will take up a sufficient quantity thereof to suitably 90 moisten the stencil-sheet after the same shall have been placed over such backing-sheet.

As indicated in the drawing, I prefer to secure the attachment edge of the stencil-sheet and carrier-sheet together for convenience of handling, and since the backing-sheet is permanently attached to the carrier-sheet, this means that the three sheets can be manipulated as a unit. With such unitary structure, as a preliminary to the typing operation in a writing-machine, it is only necessary to lay back the stencil-sheet, 100 apply the moistening compound to the back- 105

ing-sheet, replace the stencil-sheet, and then introduce the combination into the writing-machine for the stencil-cutting operation.

By assuring in the manner above set forth the smooth and unbroken surface of the backing-sheet, the stencil-sheet is brought into intimate coaction therewith throughout the whole of its under surface, and not only suitably moistened in every part but also given a firm foundation, resulting in uniformity of the type characters formed therein by the writing-machine.

Having now described my invention, what I claim as new therein and desire to secure by Letters Patent is as follows:

1. In stenciling material, the combination with a stencil-sheet, of a carrier-sheet and a soft absorbent backing-sheet between said stencil-sheet and carrier-sheet, said backing-sheet being secured to said carrier-sheet throughout substantially its entire expanse, substantially as set forth.

2. In stenciling material, the combination with a stencil-sheet, of a carrier-sheet having a coating rendering it impervious to ink, and a soft, absorbent backing-sheet between said stencil-sheet and carrier-sheet, said backing-sheet being secured to such carrier-sheet throughout substantially its entire expanse, substantially as set forth.

3. In stenciling material, the combination with a stencil-sheet, of a carrier-sheet coated to render the same impervious, and a soft, absorbent backing-sheet between said stencil-sheet and carrier-sheet, said backing-sheet being secured to said carrier-sheet by said coating, substantially as set forth.

4. In stenciling material, the combination with a stencil sheet, of a soft, absorbent backing underlying said stencil-sheet during the stencil-cutting operation, said backing being impregnated with a moistening solution containing water, glycerin and Turkey-red oil, substantially as set forth.

5. In stenciling material, the combination with a stencil-sheet, of an impervious carrier-sheet of hard, firm material, and an absorbent backing-sheet secured to said carrier-sheet throughout substantially its entire expanse, said backing-sheet being moistened by a solution containing water, glycerin and Turkey-red oil, substantially as set forth.

This specification signed and witnessed this 21st day of March, 1913.

ALBERT B. DICK.
